CLAIM

We claim the ornamental design for a knee brace, as shown and described.

DESCRIPTION

FIG. 1 is a front view of a knee brace showing my new design;

FIG. 2 is a back view thereof with the lower fastening strap fastened;

FIG. 3 is a left side view thereof with the lower fastening strap laid flat; and,

FIG. 4 is a right side view thereof with the lower fastening strap laid flat.

The broken lines in the drawings represent environmental structure and form no part of the claimed design.
